UNITED STATES PATENT OFFICE.

GARRETT C. MASON, OF DOS PALOS, CALIFORNIA.

NECKTIE-FORM.

1,241,413.

Specification of Letters Patent. Patented Sept. 25, 1917.

Application filed April 3, 1916. Serial No. 88,599.

To all whom it may concern:

Be it known that I, GARRETT C. MASON, a citizen of the United States, residing at Dos Palos, in the county of Merced and State 5 of California, have invented certain new and useful Improvements in Necktie-Forms, of which the following is a specification.

This invention relates to an improved form of neck-tie holder, which has for its principal object the construction of a simple and efficient form over which the tie may be placed to form a neat and natural appearing knot.

Another object of my invention is to so 15 construct the form that it is secured to the collar button in such a manner that there is no danger of it dropping out of position.

Still another object of the invention is to 20 construct the form of a single sheet metal stamping.

With these and other objects in view my invention consists in the novel construction, combination and arrangement of parts herein illustrated and more particularly pointed 25 out in the appended claims.

Reference being had to the accompanying drawing forming a part of this specification,

Figure 1 is a view in front elevation showing my improved form with the tie in position thereon.

Fig. 2 is a view in perspective showing the rear of the form.

Fig. 3 is a top plan view.

Fig. 4 is a view in rear elevation.

Fig. 5 is a view in horizontal section taken 35 just below the wings of the form.

Fig. 6 is a view in section on the line 6—6, Fig. 4.

Referring to corresponding parts in the 40 several views by the same numerals of reference, 1 denotes the front portion of a form consisting of the elongated convex plate 2, on the top portion of which is formed the wings 3. These wings extend laterally and 45 rearwardly to conform to the curvature of the collar and are extended slightly upward in order to contact with the inside of the collar fold. The rear portion of the form, is denoted by 4, and is also slightly convexed, 50 as shown at 5, and provided with a central opening 6, below which is a converging slot 7

communicating with the hole 6 through the contracted passageway 8. This portion 4 is formed integrally with the front portion 2, is bent along the top edge of the latter, and 55 has the outer edges 9 crimped around the sides of the front portion 2.

In use the approximate center of the tie is placed over the front portion 2, and the two ends carried to the back of the form, then 60 folded upwardly and around the top of the form and then tucked down between the central portion of the tie and front of the form 2, as shown in Fig. 1. The form is then placed in position by inserting the wings 3 65 between the folds of the collar and entering the hole 6 over the collar button, thus securely holding it in position.

From this description it will be apparent that I have provided a device on which a tie 70 may be formed to give a neat and natural appearing knot, and which is securely held in position in the collar.

While I have shown and described the preferred embodiment of my invention it will 75 be understood that minor changes in detail and form within the scope of the claims may be resorted to without departing from the spirit of the invention.

What I claim and wish to cover by Letters 80 Patent is:—

1. A necktie form comprising a concavo-convex front plate provided with laterally extended curved wings shaped to be passed beneath a collar, and an oppositely curved 85 concavo-convex rear plate integrally connected with the front plate at the top and side edges, said rear plate having a button engaging slot.

2. A necktie form comprising a sheet 90 metal plate folded to provide front and rear plates, said plates being of concavo-convex form and of opposite curvature, the side edges of one of said plates being folded over the contiguous edges of the other plate, the 95 front plate having laterally extended curved wings shaped to be passed beneath a collar, the rear plate having a button-engaging slot.

In testimony whereof I affix my signature. 100

GARRETT C. MASON.
